UNITED STATES PATENT OFFICE.

BARTON P. JENKS, OF ATTLEBORO, MASSACHUSETTS, ASSIGNOR TO THE WATSON COMPANY, OF ATTLEBORO, MASSACHUSETTS.

DESIGN FOR A SPOON, FORK, OR SIMILAR ARTICLE.

53,659.

Specification for Design.

Patented July 29, 1919.

Application filed May 10, 1919. Serial No. 296,249. Term of patent 14 years.

To all whom it may concern:

Be it known that I, BARTON P. JENKS, a citizen of the United States, residing in Attleboro, county of Bristol, and State of Massachusetts, have invented a new, original, and ornamental Design for a Spoon, Fork, or Similar Article, which is illustrated in the accompanying drawing, forming part of this application.

Figure 1 in the drawing is a view of the

design in front elevation. Fig. 2 is a fragmentary perspective view on the line A—A of Fig. 1.

I claim:

The ornamental design for a spoon, fork, or similar article as shown.

BARTON P. JENKS.

Witnesses:

JAMES L. BRIGGS,
F. R. WOODWARD.
